Patented Jan. 28, 1919.

UNITED STATES PATENT OFFICE.

CHARLES A. BRICKLEY, OF PROVIDENCE, RHODE ISLAND.

KEYHOLE-GUARD.

1,292,696.

Specification of Letters Patent. Patented Jan. 28, 1919.

Application filed September 21, 1918. Serial No. 255,039.

To all whom it may concern:

Be it known that I, CHARLES A. BRICKLEY, a citizen of the United States, residing at Providence, in the county of Providence and 5 State of Rhode Island, have invented a new and useful Improvement in Keyhole-Guards, of which the following is a specification.

This invention relates to certain new and useful improvements in a key hole guard, 10 which is insertible in the key hole and lockable therein, the principal object residing in the improved and novel construction and the manner of forming and assembling the parts into a simple and compact device.

15 The invention consists of a housing or casing stamped from sheet metal which is bent or folded upon itself to form a cylindrical chamber and a depending wing, a key-barrel rotatable within the chamber of 20 the casing, a retaining lug carried by the barrel for rotation from registry with the wing into locking relation with the door, and key-controlled means for locking the barrel against rotation within its chamber.

25 Further, the invention is found in the features of construction and the arrangements and combinations of parts hereinafter described and claimed, reference being had to the accompanying drawing wherein—

30 Figure 1 is a side elevation of the improved keyhole guard.

Fig. 2 is a transverse section thereof on line 2—2 of Fig. 1.

Fig. 3 is a similar view taken on line 3—3 35 of Fig. 1.

Fig. 4 is a plan view of the blank for the guard casing, the parts 8 having been removed after the formation of the blank, and

Fig. 5 is an end elevation thereof.

40 Referring more in detail to the drawing, the numeral 1 designates the blank of sheet metal from which the casing or body is formed. This blank, while in its flat condition, is stamped to divide it into a central

45 longitudinal portion 2 and bordering side portions 3. The central portion consists of a narrow section and a wide section which, when rolled or bent into final shape, form two cylinders 4 and 5 interposed by one of 50 a pair of beads 6 that include the larger cylinder 5. Each side portion 3 is stamped to provide a series of semi-cylindrical raised portions 7 which extend in parallelism from the central portion, within the beads 6, to

55 the edge of the side, the raised portions 7 of one series being alined with those of the

opposite series whereby when the blank assumes its final shape, the two series will oppose and supplement one another in forming a like member of pin-receiving cylindrical 60 chambers. The side portions are also provided with registrable cut-outs or openings 8. These various shapes are expeditiously performed by one or two simple stamping operations while the blank is in its flat condition. 65

The final shaping operation on the blank resides in bending it upon itself to form the cylindrical chambers 4 and 5 and a depending wing part, the latter formed by bringing the sides 3 into flat contacting relation and soldering or otherwise securing them. 70

A barrel 9 is rotatably mounted in chamber 5 and has a stem extension 10 operating into cylinder 4 for supporting the retaining 75 lug or latch 11 in the opening 8. The barrel 9 is provided with a key slot 12 and establishing communication between the latter and the pin chambers 7 are transverse bores 13. Operable in these bores and chambers 80 are upper and lower sets of co-operating locking pins 14 and 15 which are yieldably supported on coiled springs 16 within the chambers 7 the lower ends of the latter being closed as by plugs 17. 85

In operation with the key 18 in the slot 12 and the retaining latch 11 alined with the wing 3 in its opening 8, the guard device is inserted in the key hole of a door, or the like, in a manner similar to inserting a key. 90 When properly disposed, the key 18 is turned to rotate the retaining latch 11 into interlocking relation with a fixed part of the door lock whereby the guard is firmly fixed against unauthorized removal. The key hole 95 is thus securely closed against the insertion of a tool or skeleton key by which the door lock might otherwise be rendered inoperative.

Having thus described my invention, what 100 I claim as new and desire to secure by Letters Patent is—

A key hole guard comprising a casing constructed from a sheet of metal bent to form an inner cylinder and a larger and 105 alined outer cylinder joined thereto by a bead-like shoulder, the edge portions of the sheet being brought together to provide a depending web, said edge portions being fluted to form pin chambers leading through 110 the web from the outer cylinder, plugs closing the lower ends of the pin chambers to

reinforce the same, a barrel rotatably fitting the outer cylinder and provided with a reduced stem extending within the inner cylinder, said barrel having an axial key slot 5 and radial bores leading therefrom for registry with the pin chambers, coöperating locking pins slideable in the bores of the barrel and the pin chambers of the web, springs arranged on the plugs within the chambers 10 to expand against the pins, and a guard retaining lug carried radially by the barrel stem and extending through a peripheral

opening formed in one side only of the inner barrel, said opening extending down into the underlying web whereby the retaining lug may be swung from alinement with the web to one side only thereof. 15

In testimony whereof I have signed my name to this specification in the presence of two subscribing witnesses.

CHARLES A. BRICKLEY.
